Patented Mar. 27, 1928.

UNITED STATES PATENT OFFICE.

GIDEON RIETVELD, OF KNOXVILLE, IOWA.

MATCH-BOX HOLDER.

Application filed May 25, 1926. Serial No. 111,529.

The object of my invention is to provide a match box holder of simple, durable and inexpensive construction which may be formed of a single piece of sheet metal, and so arranged that a box of matches may be inserted therein, and to provide means whereby the matches may be easily and quickly removed after being inserted, and at the same time provide means for protecting the building against fire in case the matches should become ignited.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a perspective view of my improved match box holder.

Figure 2 is a perspective view showing the match box holder open for receiving a box of matches.

Figure 3 is a detail, longitudinal, sectional view showing the match box holder open.

Figure 4 shows the shape of the blank from which the match box is formed.

My improved match box holder comprises a back portion 10 and a front portion 11, said back and front portions being connected by a top portion 12. The back 10 is provided with side members 13 and a bottom member 14. Each side edge of the side members 13 is provided with a segmental projection 15 which serves to form ends for a chute through which the matches are removed.

The front 11 is provided with an opening 16 which is formed by pressing out a tongue 17, said tongue being curved outwardly and upwardly, as clearly shown in Figures 1 and 3, at a slight distance from the bottom of the front member. The bottom edge of the member 11 is provided with a bottom member 18 having a slot 19, the metal forming the back edge of said slot being bent upwardly to form a catch 27, said bottom member being turned inwardly at right angles to the member 11. The front member is also provided with side members 20 which are also turned inwardly along the dotted line 21. The top edges of the members 20 are curved. The side members 13 of the back are bent forwardly at right angles to the said back and along the dotted line

22, while the bottom 14 is bent forwardly on the dotted line 23. The bottom 14 is provided with an upwardly projecting tongue 24 to form a depression 24^a. The front member 11 is folded opposite the back member 10 by bending the top member 12 with the side members 20 overlapping the side members 13, to a position substantially as shown in Figures 2 and 3.

Thus it will be seen that a considerable space is provided between the front edge of the member 14 and the back edge of the member 18 through which a box of matches may be inserted between the side members 13 with the open side of the match box adjacent to the front 11, after which the cover member may be moved rearwardly until the catch 27 enters the depressions 24^a, which serves to lock the front and back members together.

The members 15 are so located that they will project through the opening 16, having their curved edges fitting adjacent to the inner face of the member 17, and the upper curved ends of the members 20 and 13 resting adjacent to the inner surface of the curved member 12.

A slot 25 is provided in the top of the member 10 to receive a nail 26, or similar supporting device, by means of which the match box holder is detachably supported to a wall.

The match box holder may be opened by simply pressing upwardly on the member 14 through the opening 19, which will cause the catch 27 to be disengaged from the depression 24^a, then moving the lower end of the front member outwardly. Suitable beads 28 are provided for stiffening the sides and front of the match box holder.

Thus it will be seen that I have provided a match box holder of simple, durable and inexpensive construction, which is constructed from a blank formed of a single piece of sheet metal, and formed into shape by suitable forming dies, thereby providing a match box holder which may be very cheaply constructed and sold for advertising purposes.

I claim as my invention:

1. A match box holder formed of a single piece of sheet metal, having a back member and a front member, the back member being provided with side and bottom members, and the front member being provided with

105

110

side and bottom members, said side members being designed to overlap the side members of said back member, the front member being provided with an opening having at 5 its lower edge an outwardly and upwardly extending curved portion to form a chute bottom, the side members of said back member being provided with forwardly extending segmental portions to enter the opening 10 of said front member and to serve as end members for said chute.

2. A match box holder formed of a single piece of sheet metal, having a back member and a front member, the back member being 15 provided with side and bottom members, and the front member being provided with side and bottom members, said side members being designed to overlap the side members of said back member, the front member being 20 provided with an opening having at its lower edge an outwardly and upwardly extending curved portion to form a chute bottom, the side members of said back member being provided with forwardly extending 25 segmental portions to enter the opening of said front member and to serve as end members for said chute, one of said bottom members being provided with an opening, and the other bottom member provided with 30 latching means for entering said opening.

3. A match box holder formed of a single piece of sheet metal, having a front member and a back member, the upper ends of said front and back members being connected by 35 a top member, the edges of said back member being provided with forwardly extending side members each of which is provided with a forwardly extending segmental portion to form the ends of a chute, said front 40 member being provided with an opening, the lower edge of which is provided with a forwardly and upwardly extending portion designed to provide a side member for said chute, said segmental portions of said side members being designed to enter the openings 45 of said front member when the said front member is moved to position parallel with said back member, one of said front

or back members being provided with a bottom portion.

4. A match box holder formed of a single piece of sheet metal, having a front member and a back member, the upper ends of said front and back members being connected by a top member, the edges of said back member being provided with forwardly extending side members, each of which is provided with a forwardly extending segmental portion to form the ends of a chute, said front member being provided with an opening, 60 the lower edge of which is provided with a forwardly and upwardly extending portion designed to provide a side member for said chute, said segmental portions of said side members being designed to enter the openings of said front member when the said front member is moved to position parallel with said back member, one of said front or back members being provided with a bottom portion, and means for locking said front 70 and back members in a closed position.

5. A match box holder formed of a single piece of sheet metal, having a back member and a front member, the back member being provided with side and bottom members, 75 and the front member being provided with side and bottom members, said side members being designed to overlap the side members of said back members, the front member being provided with an opening having at 80 its lower edge an outwardly and upwardly extending curved portion to form a chute bottom.

6. A match box holder formed of metal having a back member and a front member, 85 the back member being provided with side and bottom members, and the front member being provided with side and bottom members, said side members being designed to overlap the side members of said back 90 member, the front member being provided with an opening having a match delivery chute.

Des Moines, Iowa, May 11, 1926.

GIDEON RIETVELD.
